United States Patent Office

Des. 196,584
Patented Oct. 15, 1963

196,584

ELECTRICAL PLUG

Edward J. Alberts, Logansport, Ind., assignor to Essex
Wire Corporation, Fort Wayne, Ind., a corporation of
Michigan

Filed July 9, 1962, Ser. No. 70,835

Term of patent 14 years

(Cl. D26—1)

FIGURE 1 is a perspective view of an electrical plug, showing my new design;

FIGURE 2 is a side elevational view thereof;

FIGURE 3 is an end elevational view thereof;

FIGURE 4 is a top plan view thereof; and

FIGURE 5 is a bottom plan view thereof.

I claim:

The ornamental design for an electrical plug, substantially as shown.
